[57] CLAIM

The ornamental design for an athletic shoe, as shown and
described.

DESCRIPTION

FIG. 1 is a side-elevational view of an athletic shoe of my
design; the other side of the shoe being a mirror image of
FIG. 1;

FIG. 2 is a bottom plan view thereof;

FIG. 3 is a top plan view thereof;

FIG. 4 is a front elevational view thereof; and,

FIG. 5 is a rear elevational view thereof.
